[57] **CLAIM**

We claim the ornamental design for a panel trim, as shown and described.

DESCRIPTION

FIG. 1 is a perspective view of a panel trim, showing our new design;

FIG. 2 is a right-hand side elevational view;

FIG. 3 is a top plan view; and,

FIG. 4 is fragmentary elevational view.

The broken lines are for illustrative purposes only and form no part of the claimed design.
